UNITED STATES PATENT OFFICE

163,175

PETTICOAT

Anna Friedman, New York, N. Y.

Application January 30, 1951, Serial No. 14,042

Term of patent 14 years

(Cl. D3—26)

To all whom it may concern:

Be it known that I, Anna Friedman, a citizen of the United States, residing in New York city, in the county of New York and State of New York, have invented a new, original, and ornamental Design for a Petticoat, of which the following is a specification, reference being had to the accompanying drawing, forming part thereof.

The figure is a front view of a petticoat showing my new design.

The rear of the petticoat is the same as the front.

I claim:

The ornamental design for a petticoat, substantially as shown and described.

ANNA FRIEDMAN.
